UNITED STATES PATENT OFFICE.

JOHN C. SHAMBOW, OF WOONSOCKET, RHODE ISLAND, ASSIGNOR TO SHAMBOW SHUTTLE COMPANY, OF WOONSOCKET, RHODE ISLAND.

SHUTTLE-EYE.

1,399,893.

Specification of Letters Patent. Patented Dec. 13, 1921.

Application filed February 12, 1921. Serial No. 444,323.

To all whom it may concern:

Be it known that I, JOHN C. SHAMBOW, a citizen of the United States, residing at Woonsocket, in the county of Providence 5 and State of Rhode Island, have invented new and useful Improvements in Shuttle-Eyes, of which the following is a specification.

This invention relates to certain new and 10 useful improvements in shuttle eyes, and the primary object thereof is to provide an eye which has means incorporated therein for stopping and cutting any bunch of thread passing to the eye.

15 In the weaving of tire fabric it is essential that there should be no knots, that is to say in the sense of a bunch woven into the fabric, and accordingly the present invention aims to provide an eye which will 20 stop and cut the bunch, or break the yarn.

A further object of the invention is to provide means for attaining the function 25 above pointed out, which can be easily and simply made or provided, and more specifically to provide for such formation by simple and opposite drilling operations.

The invention still further aims to simplify the construction of eye of this character, and to generally improve same.

30 Further and other objects will be later set forth and manifested in the course of the following description.

In the drawings:

Figure 1, is a top plan view of the invention embodied in a shuttle;

Fig. 2, is a side elevation;

Fig. 3, is a top plan view of the eye partially formed and shown removed from the shuttle, and

40 Fig. 4, is a section on line 4—4 of Fig. 3.

In proceeding in accordance with the present invention, an eye is employed which has an axial thread passage 1, a radial slot 2 leading into the passage and a diagonal cut 45 or slot 3, while the periphery of the eye is reduced in diameter at 4, the slot 3, terminating in the guide hole 5. The opposite end of the eye is threaded at 6, to permit same to be secured in position and removed 50 at will.

The interior of the passage 1, is provided with a pair of somewhat sharp cutting points 7, which extend inwardly toward each other in confronting relation and are 55 spaced to allow the thread to pass there-

between as shown in Fig. 4, of the drawings. These points or extensions are formed by first boring or drilling from each end of the body with a bit having a point to cut or form approximately V-shaped bottoms indicated at 7^a, in Fig. 3, following which the thread 6, is formed or cut; the slot 3 and the guide hole 4, next formed, and finally the radial slot 2, the latter passing through the web 8, formed by the bored parts 7^a, to thus provide the space 9, separating the cutting points or extensions as depicted in Fig. 4.

In operation, the thread passes from the bobbin and through the throat into the slot 3 and guide eye 5, and thence enters the passage 1, and out from the delivery side of the eye. If, in its passage through the space 9, the thread should have a bunch or the like, same will be caught by the 75 points or projections 9, and cut, thus preventing the weaving of knots or bunches into the fabric. In order to prevent accidental unthreading, a ledge 10, is formed in the shuttle body and extends above the peripheral cut-out 4, so as to thereby guide the 80 yarn or thread.

From the above it will be apparent that the thread is not only cut if possessed of bunches or knots, but in addition means are 85 provided to prevent accidental unthreading, and at the same time, a unitary structure is provided which can be simply and easily made and at slight cost.

Having thus described my invention, what 90 I claim as new and desire to secure by Letters Patent is:

1. In a shuttle, an eye having an axial passage and formed with a radial slot leading thereto and a diagonal slot terminating in a guide hole, and having a peripheral cut-out extending from the radial slot upwardly, a guard borne by the shuttle body and extending above the lower end of the peripheral cut-out, and a pair of cutting 100 projections extending into the axial passage and having their free ends confronting and spaced and formed to permit the passage of the yarn and to cut same upon any bunches or knots borne by the yarn encountering the projections.

2. In a shuttle, an eye having an axial thread passage and having a web extending across its interior, said eye having a transverse slot and a radial slot, the latter extend- 110

ing diametrically through the web and communicating with the transverse slot.

3. In a shuttle, an eye having a thread passage and a pair of diametrically opposed approximately segmental shaped thread cutters in the passage extending inwardly from the circumferential wall of the passage and having their chords free and spaced apart.
4. In a shuttle, an eye having a thread-receiving passage and a slotted web in the passage formed to receive the thread in said slot, said web having opposed concave faces to form cutting parts to cut bunched or knotted portions in the thread.
5. In a shuttle, an eye having a thread-receiving passage extending axially thereof, a web in the passage, and a radial slot leading into the passage and diametrically through the web to divide the latter, the web divisions having parts to form cutting portions.
6. In a shuttle, an eye having an axial thread passage, a radial slot extending axially of the eye and leading from the passage through the periphery of the eye, a

peripheral cut-out extending from the slot up along side of the eye, and a transverse slot formed in the eye and terminating in a guide hole, one end of the transverse slot extending into the radial slot.

30

7. In a shuttle, an eye having a bore extending inwardly from each end to leave a web therebetween, the latter having opposed concave faces, the bores forming a thread passage, the eye having a slot extending 35 into the passage and through the web.

8. In a shuttle, an eye having an axial thread passage and having a web extending across its interior and having a cut to form a pair of opposed cutting members therein 40 each having a free end, and having their free ends spaced from one another.

In testimony whereof I have signed my name to this specification in the presence of two subscribing witnesses.

JOHN C. SHAMBOW.
